UNITED STATES PATENT OFFICE.

JOHN McDERRAID, OF ROCKFORD, ILLINOIS.

CLOSURE FOR CHURNS.

SPECIFICATION forming part of Letters Patent No. 390,689, dated October 9, 1888.

Application filed July 23, 1888. Serial No. 280,766. (No model.)

To all whom it may concern:

Be it known that I, JOHN McDERRAID, a citizen of the United States, residing at Rockford, in the county of Winnebago and State of Illinois, have invented certain new and useful Improvements in Closures of Churns, of which the following is a specification.

This invention relates to an improved means of securing the closures or covers to churns; and it consists of certain new and useful constructions and combinations of parts, which are hereinafter described, and pointed out in the claim.

Referring to the accompanying drawings, which form a part of this specification, Figure 1 is a plan view of my improved churn-cover secured to the ring-head of a churn. Fig. 2 is a view of a vertical section of the same through the dotted line X X of Fig. 1. Fig. 3 is a view of an elevation of the cover and ring-head to which the former is secured. Fig. 4 is an isometric view, in detail, of a portion of the churn-cover fastening shown in the foregoing views.

Like letters of reference indicate corresponding parts throughout the several views.

A is a ring-head, having the periphery thereof beveled to enter the croze of a churn.

A' is an annular flange projecting from the upper side of the ring-head A, which has a circular opening, A², therethrough, of the same diameter as the inside of the annular flange A'.

A³ represents ears projecting vertically from the upper side of the ring-head A and having horizontal circular openings A⁴ in the same to admit parts to be described hereinafter. The ring-head is permanently seated in the chine of a churn, (not shown,) and the ears projecting therefrom are preferably integral therewith.

B is a disk-head, which forms the basis of the churn-cover and has a vertical bolt-hole, B', through the center thereof.

B² is a metallic casing inclosing the periphery and upper peripheral angle of the disk-head B.

B³ is a transverse strengthening-brace integral with the casing B² and extending across the center of the disk-head B. 50

B⁴ is a vertical stud, also integral with the brace B³, and having a cylindrical passage, B⁵, extending longitudinally therethrough.

B⁶ is a ring of cork set into the disk-head B, which engages with the annular flange A' and 55 forms a tight joint therewith.

C represents bails for securing the cover to the ring-head A, mounted in the ears A³ thereon by inserting the ends of the former through the openings A⁴ in the latter. These bails 60 may be swung outward or inward, as indicated by the dotted lines X' of Fig. 1, according as it is desired to open or close the churn.

D is a bolt passed through the openings B' B⁵ in the disk-head and vertical stud, and is 65 secured in position by means of the set-nut D'.

E is a fulcrum having a threaded passage, E', extending vertically therethrough to adapt it to engage with the threaded portion of the bolt D to form a vertical adjustable swivel-joint therewith for the former to revolve upon. 70

F is a lever-cam, consisting of the cam F', pivoted to the swiveled fulcrum E by means of the horizontal pivot F² and openings F³ in the cam F', and the lever F⁴, integral therewith, for operating the same. The cam F' is divided by a central longitudinal cleft, F⁵, which admits the fulcrum E, whereto it is pivoted, and embraces the set-nut D', thereby preventing said nut from working loose and serving as a wrench to remove and replace the same, if desired. To take up the slack between the bails and cam or wear of any of the parts composing the fastening mechanism, elevate the lever-cam to a vertical position and 75 revolve it and the fulcrum whereto it is swiveled upon the bolt D, as indicated by the dotted circle X³ in Fig. 1, until the slack or wear is taken up.

When it is desired to remove the cover from 90 the churn, turn the lever-cam F, as indicated by the dotted lines X² in Fig. 3, whereupon the bails C will be unlocked. Next swing the bails outward, as indicated by the dotted lines

X' in Fig. 1. Then grasp the cam-handle F', elevating it to a vertical position, and lift the cover from the churn thereby.

I claim—

5 The combination, with a churn having a ring-head provided with swinging bails seated therein, of a cover adapted thereto and provided with a peripheral casing and having a vertical stud, B⁴, mounted thereon, a vertical

bolt, D, passed through said cover and stud, to a set-nut, D', to secure said bolt in place, the fulcrum E, swiveled to said bolt, and a lever-cam, F, pivoted to said fulcrum, substantially as set forth.

JOHN McDERNAID.

Correction in Letter Patent No. 390,689.

It is hereby certified that the name of the patentee in Letters Patent No. 390,689, granted October 9, 1888, for an improvement in "Closures for Churns," should have been written and printed *John McDermaid* instead of "John McDernaid," and that the said Letters Patent should be read with this correction therein that the same may conform to the record of the case in the Patent Office.

Signed, countersigned, and sealed this 18th day of December, A. D. 1888.

[SEAL.]

H. L. MULDROW,
First Assistant Secretary of the Interior.

Countersigned:

BENTON J. HALL,
Commissioner of Patents.
